UNITED STATES PATENT OFFICE.

ADOLPH G. CARLSON, OF CHICAGO, ILLINOIS.

SACK-CLEANING DEVICE.

1,173,250.

Specification of Letters Patent. Patented Feb. 29, 1916.

Application filed October 21, 1915. Serial No. 57,096.

To all whom it may concern:

Be it known that I, ADOLPH G. CARLSON, a citizen of the United States, and resident of Chicago, in the county of Cook and State 5 of Illinois, have invented certain new and useful Improvements in Sack-Cleaning Devices, of which the following is a specification.

My invention relates to dust separating 10 devices and has particular reference to a novel sack cleaning apparatus designed particularly for use in cement mills.

In the manufacture of cement it is common to require the return of the sacks in 15 which the cement is shipped, then to utilize the sacks for further shipments of cement. However, these sacks, when returned, usually contain more or less cement, sometimes in the form of hardened lumps or particles, the 20 presence of which in the cement would be deleterious. It is, therefore, desirable to remove the dust from the sacks in order that they may be filled with fresh material which contains no deleterious substance.

I have conceived that the dust may be removed from the sack in a simple and economical manner and without materially injuring the sacks, and the present apparatus is designed with that object in view.

The invention will be more readily understood by reference to the accompanying drawings, wherein—

Figure 1 is a side elevation, partly in section, showing the apparatus which I 35 construct employing in the separation of dust from cement sacks; Fig. 2 is a section on the line 2--2 of Fig. 1; Fig. 3 is a section on the line 3--3 of Fig. 1; Fig. 4 is an enlarged sectional elevation of the feeding mechanism, 40 and Fig. 5 is a section on the line 5--5 of Fig. 1.

Referring more particularly to the drawings, it will be seen that I provide the following instrumentalities: First, a feeding 45 and counting mechanism; second, a vibrating or beating mechanism; third, a mechanism for separating the dust from the sacks and delivering the sacks out of the path of the dust; fourth, a suction fan, and fifth, a 50 dust separator of any approved form.

The feeding mechanism may comprise an endless conveyer 10, on which a sack is laid and by means of which the sack is carried between two pairs of rolls 11, 12. Any 55 lumps of cement which may be contained in the sack are crushed by these rolls and the

cement may be more readily removed therefrom. After passing out of the grasp of the last pair of crushing rolls the sack falls into a hopper 13, at the lower end of which 60 a grid 14 is pivoted, the grid being held in the position shown in Fig. 4 by means of the coiled spring 15. The passage of the air through the hopper, as induced by the fan, is momentarily interrupted by the sack 65 which lies on the grid, whereupon the grid is rocked by the suction of the air and the sack pulled into the beating or cleaning device. A link 16 connects the grid to a counting device 17, best shown in Fig. 1, the 70 counting device being actuated each time a sack is drawn into the cleaning device.

The cleaning device comprises a casing arranged in the present instance in the form of three vertical legs 18, 19, 20, connected at 75 their ends and provided interiorly thereof with corrugated metal guides 21 bent to provide a tortuous passage. As the sack is drawn forcibly through the cleaner, it is projected against the corrugations and contacts the numerous angularities of the passage, the effect of beating the sack being secured thereby.

After leaving the last vertical leg 20 of the cleaning device, the sack and the dust 85 pass to the goose neck 22 into the separating device, best shown in Figs. 1 and 2, which comprises a double conical casing 23, around the axis of which are arranged a 90 plurality of rods 24, closely disposed in circular outline, the space inclosed by the rods being of substantially the diameter of the conduit 22. These rods extend downward in the casing 23 into an inner truncated conical hopper 25, at the lower end of which is 95 mounted a pair of feeding-out rolls 26, 27, the roll 26 being resiliently mounted to permit the passage of the bags between the rolls. At the edges of the rolls I provide an apron 28, which prevents the entrance of air 100 at that point. At the lower end of the casing 23 I provide an outlet pipe 29, which communicates directly with the exhaust fan 30. A pipe 31 connects the exhaust fan with a dust separator 32, which may be of any 105 approved form. In the form shown, the cement which is separated from the sack is discharged out of the lower end 33 of the separator, while the air is blown out of the upper end 34. A source of power, indicated 110 at 35, provides means for the operation of the fan and the feeding-out rolls.

The operation is as follows: A bag, indicated at 36 in Fig. 4, is placed on the conveyor 10, is fed between the rolls 11, 12, and any hard particles crushed, whereupon the bag falls upon the grid 14 and is pulled into the cleaning device by the exhaust fan. As the sack passes through the cleaner it is beaten against the corrugated and angular sides thereof and the dust loosened from the sack, the dust and the sack being carried in the current of air to the sack separating device, at which point the air and the dust which is carried in suspension passes out to the exhaust fan, while the sack is projected in a straight line past the rods 24, into the feeding-out rolls.

A cleaning device, such as illustrated, is of simple construction and requires but a small amount of power for its operation.

20 There are no parts which readily become out of order and it requires but slight attention other than to the extent of feeding the bags into the machine.

It is obvious that many modifications may 25 be made in the construction shown, and such modifications as are within the scope of my claims I consider within the spirit of my invention.

I claim:

30 1. In a sack cleaning device, the combination of a casing providing a tortuous passage, means for feeding a sack into one end of said passage, means for inducing a current of air through said passage, whereby 35 said sack is drawn bodily through the casing, and means for separating the sack from the current of air, substantially as described.

2. In a device of the class described, the combination of a casing providing a passage of angular outline, a plurality of rounded projections into said passage, means for inducing a current of air through said passage, and means for separating the device to be cleaned from the air and the material removed from the device, substantially 45 as described.

3. In a sack cleaning device, the combi-

nation of a casing providing a tortuous passage, the material composing the casing being corrugated, thereby providing a multitude of rounded projections against which the sack is forced in its passage through the casing, and means for separating the sacks and the dust, said means including mechanism whereby the sack is caused to travel forward in a straight line, while the dust and air are deflected at an angle, and means for inducing a current of air through said casing, substantially as described.

4. In a sack cleaning device, the combination of a plurality of vertical conduits joined at their ends, said casing being lined with a corrugated material and shaped to provide a tortuous passage, means for inducing a current of air through said passage, and means for separating a sack from the current of air and the dust carried thereby, said means including a casing which is flared at one point and a series of rods in the flared portion of said casing, said rods serving to guide said sack in a straight line, the air and dust being taken off at an angle to the line of travel of the sack, and feeding-out rolls by means of which the separating device is sealed and the sack fed out therefrom, substantially as described.

5. In a sack cleaning device, the combination of a casing, a plurality of lateral projections into said casing, means for generating a current of air through said casing, whereby a sack is carried therethrough, and separating means whereby the sack and the dust removed therefrom are separated, said separating means including a casing having an axial inlet and outlet and an angularly disposed outlet, and sack guiding means located in the line of the axial inlet and outlet, substantially as described.

Signed at Chicago, Illinois, this 18th day of October, A. D. 1915.

ADOLPH G. CARLSON.
